UNITED STATES PATENT OFFICE.

MARRS MCLEAN, OF BEAUMONT, TEXAS.

WELL-SCREEN.

1,367,406.

Specification of Letters Patent.

Patented Feb. 1, 1921.

Application filed March 1, 1920. Serial No. 362,384.

To all whom it may concern:

Be it known that I, MARRS MCLEAN, a citizen of the United States, residing at Beaumont, in the county of Jefferson and 5 State of Texas, have invented certain new and useful Improvements in Well-Screens, of which the following is a specification.

My invention relates to well screens and has for an object to provide a screen of improved type, adapted to restrain sand and other matters upon the exterior thereof of 10 different sizes without materially interfering with the inflow of liquid.

The further object of the invention is to 15 provide a screen consisting of a section of pipe having screen materials of different mesh, the coarser mesh upon the exterior of and spaced from the material of finer mesh whereby the outer, coarser screen restrains 20 the sand, shale or like material of large dimensions with a finer screen within the outer screen for restraining sand or like material of smaller dimensions.

Another object of the invention is to 25 provide a screen in nature of a double screen built on or over any type of screen made on pipe section by re-wrapping about first screen a coarser mesh wire and spacing same from the first or inner screen by supporting bars, 30 the coarser outside screen restrains shales and mucky materials of larger dimensions, which would muck the first or inside screen of any type, while the first or inner screen restrains sands and like materials of smaller 35 dimensions.

Another object of the invention is to provide furrows in pipe section within which to place or fuse supporting longitudinal or circumferential bars over which wire is 40 wrapped, the furrow preventing any slipping of the bars, any slipping of which would serve to throw the wire mesh out of gage, or cause them to be easily displaced.

Another object of the invention is to 45 provide a screen on a pipe section divided into compartments by circumferential bars at spaced intervals, so that if the wire on one section of screen is displaced and sand or other material fill the compartment where 50 the wire is displaced, the circumferential bars will keep such sand and materials from filling and making useless other compartments.

With these and other objects the invention 55 comprises certain novel parts, units and

combinations as will be hereinafter more fully described and claimed.

In the drawings,

Figure 1, is a view of the strainer in side elevation, certain parts being broken away, 60 the particular type of screen there shown being the "button" screen.

Fig. 2, is a transverse sectional view taken on line 2—2 of Fig. 1.

Fig. 3, is a transverse enlarged, detail 65 sectional view through one of the buttons on the same plane as Fig. 2.

Fig. 4, is a view of a slightly different type in side elevation, parts being broken away.

Fig. 5, is a transverse sectional view taken on line 5—5 of Fig. 4.

Like characters of reference indicate corresponding parts throughout the several views.

The improved well strainer which forms the subject matter of this application is of the type in general use which comprises a pipe 10, threaded as at 11, for a coupling. This pipe may be of any length desired, the 80 lower section being broken off to indicate such indefinite and indeterminate length.

The pipe section 10, is provided with a plurality of perforations which may be cylindrical as indicated at 12, at Fig. 5, or 85 may be tapered as indicated at 13, at Figs. 2 and 3. The tapered openings are used in conjunction with the button type of strainers indicated at 14. The button strainer unit 14, having tapered side walls complementary to the tapered walls of the perforation 13, forms an improved type button strainer whereby the button is capable of standing a greater external pressure than the ordinary button unit which is seated in a 95 cylindrical opening bearing upon a shoulder having its opening smaller in diameter than the opening which receives the button.

The present invention is not limited to the button type of strainer but as that type is 100 included in the invention it will be first described.

Between the several rows of perforations 13, which receive the buttons 14, furrows are formed in the periphery of the pipe as 105 indicated at 15, at Fig. 2. Within these longitudinal furrows are seated bars 16, preferably composed of solder or other easily fusible metal retained in the furrows by being inserted or fused therein. The en- 110

- tire bar 16, is composite in nature being built up first of the section 17, as indicated at Fig. 1. Over this partially completed bar the outer screen is applied. As shown 5 in the drawings this outer screen is of the wound wire type. It is to be understood that while the wound wire type of screen is at present considered the desirable screen for the purpose the invention is not limited 10 to that type of screen. The screen is placed upon the bar sections 17, by winding thereon in the usual manner. After winding upon the bar 17, the screen so wound is secured by solder whereby the bar 16, is completed 15 by fusing into the interstices of the screen other metal 18. The sections 17 and 18, forming an integral or homogeneous structure, complete the entire bar 16, having the wires 19, of the outer screen fused 20 therein. The bars 16 hold the screen composed of the wires 19, not only against displacement relative to the pipe 10, but also spaced away from the pipe 10, and the buttons 14.
- 25 Circumstantial bars 20 are also preferably employed at spaced intervals along the pipe 10, producing between the bars 20, and the bars 16, compartments. These bars being completed by fusing solder into the intervals 30 between the wires 19. These compartments are important to the present invention in that should the outer screen become fractured or the wire displaced, entering sand or the like will fill one single compartment 35 the other compartments remaining useful even though one compartment may be filled beyond utility.
- In the type of screen shown at Fig. 4, the bars 21, corresponding to the bars 16, are 40 triple instead of double in nature. A section is first introduced into the furrows of the pipe 10, and a fabric or wire wrapped screen 22, wound thereon. This fabric or wire wrapped screen is secured to the first 45 layer of the bars 21, by soldering and other bar sections 23, are then secured upon the exterior of the fabric or wire wrapped screen 22. The outer screen is then wound on and consists of the wires 19, or of any 50 approved type of external screen. The interstices of this outer screen are filled the same as described in Figs. 1, 2 and 3, forming a continuous homogeneous composite rib 21, from the bottom of the furrows to 55 the external periphery of the external screen. The circumferential ribs 20, are employed in this type of screen the same as in the type of screen previously described and for the same purpose.
- 60 It will be noted especially from Fig. 5, that the composite bars 21, space the fabric or wire wrapped screen 22, away from the

pipe 10, and the outer screen composed of the wires 19, away from the screen 22, whereby the greatest amount of utility is 65 provided in both of such screens. As indicated at Fig. 4, the inner screen 22, is intended to be of fine mesh and the outer screen of coarser mesh for the purpose hereinbefore disclosed. 70

In use the screen constructed as hereinbefore described is employed in the usual well-known manner of using well screens.

I claim,

1. A well screen comprising a pipe section having perforations therethrough, bars extending longitudinally of the pipe and rigidly secured thereto, screen material interposed between the bars and other screen material secured to the outer peripheral 80 surface of the bars and spaced from the periphery of the pipe and from the first mentioned screen material.

2. A well screen comprising a pipe section having perforations therethrough, bars 85 extending longitudinally of the pipe and fused thereto, screen material covering the perforations and disposed between the bars and other screen material fused to the outer peripheral surfaces of the bars and spaced 90 from the pipe and from the first mentioned screen material.

3. A well screen comprising a section of pipe having perforations therethrough and furrows extending longitudinally thereof, 95 screen units seated in the perforations, bars seated and fused in the furrows and screen material carried upon and fused to the peripheral surfaces of the bars and spaced from the pipe and the screen units. 100

4. A well screen comprising a pipe, ribs extending longitudinally of the pipe and supporting screen material spaced from the pipe and circumferential ribs extending between the longitudinal ribs and forming 105 with the longitudinal ribs and the screen, compartments between said screen and the pipe.

5. A well screen comprising a pipe having perforations, an outer screen concentric 110 with the pipe and spaced therefrom and longitudinal and circumferential ribs interposed between the screen and the pipe and forming compartments.

In witness whereof, I have hereunto set 115 my hand and seal at Lake Charles, Calcasieu parish, Louisiana, this 18th day of February, A. D. nineteen hundred and twenty.

MARRS McLEAN. [L. S.]
